SHORT CIRCUITING DEVICE

Filed Feb. 16, 1939

UNITED STATES PATENT OFFICE

2,216,068

SHORT CIRCUITING DEVICE

Robert B. Cummins, Kokomo, Ind.

Application February 16, 1939, Serial No. 256,799

1 Claim. (Cl. 173—328)

This invention relates to a short circuiting or cut-out device for use in short circuiting an electrical circuit.

An object of this invention is to provide a short circuiting or cut-out device adapted to be interposed in an electrical circuit and particularly in an electrical circuit connected to an alarm or signaling box.

Another object of this invention is to provide a short circuiting or circuit bridging device of this kind which is adapted to be positioned closely adjacent a signal box such as a fire alarm box or the like for the purpose of permitting the short circuiting of the electric circuit leading to the box so as to thereby eliminate the necessity of a repair man climbing a pole in order to bridge the electric circuit so as to permit repair work being done on the signal apparatus in the box.

A further object of this invention is to provide a short circuiting or cut-out means for a fire alarm system or similar electric circuit which will permit the shorting of the electric circuit to the signal device in order to admit removal of the signal device if such removal is necessary to repair the same without requiring the linesman to either climb a pole or to open a manhole cover to cut out the signal circuit to the box in the manhole cover.

A still further object of this invention is to provide a device of this kind which has a removable and reversible cover for the housing enclosing the bridging means so that when the circuit has been bridged or shorted, the box closure will indicate the condition of the signal device associated therewith.

To the foregoing objects and to others which may hereinafter appear, the invention consists of the novel construction, combination and arrangement of parts as will be more specifically referred to and illustrated in the accompanying drawing wherein is shown an embodiment of the invention, but it is to be understood that changes, variations and modifications may be resorted to which fall within the scope of the invention as claimed.

In the drawing:

Figure 1 is a detail front elevation of a short circuiting or cut-out device constructed according to an embodiment of this invention connected to a fire alarm or similar signal device,

Figure 2 is a sectional view taken on the line 2—2 of Figure 1,

Figure 3 is a sectional view taken on the line 3—3 of Figure 2,

Figure 4 is a detail front elevation partly bro-

ken away of the device showing the cover or closure in normal position, and

Figure 5 is a fragmentary front elevation of the bridging members associated with this device.

Referring to the drawing, the character F designates generally a fire alarm box or similar signal device which has a pair of conductors 10 and 11 connected thereto. The fire alarm box is also provided with the usual closure 13 provided with 10 a glass 12 which is adapted to be broken so as to permit entrance into the supplemental box carrying the usual key for opening the front of the alarm box F to operate the signaling means enclosed in the box.

At the present time where the conductors 10 and 11 are connected to overhead wires, when the signaling means in the alarm box F gets out of order, it is necessary in order for the repair man to work on the signaling means to climb a pole and connect a bridging or jump wire to the two conductors 10 and 11 at the point where the conductors 10 and 11 are connected with the pole. In certain instances, the conductors 10 and 11 extend from the bottom of the alarm box F and are then connected to underground wires and where this is the case, it is necessary in order to repair the mechanism in the box F for the repair man to enter a manhole and there bridge the conductors 10 and 11.

In order, therefore, to provide a means which may be connected to the alarm box F whereby when the signaling means in the alarm box gets out of order, the repair man can easily and quickly bridge the conductors 10 and 11, I have provided a housing generally designated as 14. The housing 14 is provided with a top wall 15, end walls 16 and a bottom wall 17. A closure plate 18 is mounted on the open front of the housing 14 and a rear wall 19 is formed integral with the end walls 16 and the upper and lower walls 15 and 17 respectively. The housing 14 is provided with a boss 20 at each front corner thereof and screws or fastening members 21 are threaded into the bosses 20 so as to removably mount the closure or plate 18 on the front of the housing 14. The plate 18 on one face thereof is provided with indicia 22 in the form of a legend "Out of order" and the opposite face of the plate or closure 18 may be plain or provided with any other indicia.

The housing 14 is provided with a boss or bushing 23 in the central portion of the upper wall 15 thereof in which a conduit 24 is adapted to be threaded. The conductors 10 and 11 are 55

adapted to extend through the conduit 24 and the bushing 23 into the housing 14. The bottom wall 17 is provided with a bushing or boss 25 through which a conduit 26 extends and is secured by nuts 26a and 26b. This conduit 26 may be threaded into the upper wall of the alarm box F and the conductors 10 and 11 are adapted to pass through the conduit 26 into the alarm box F.

The housing 14 is provided on the interior 10 thereof with an insulated plate 27 which is in the present instance secured to the rear wall 19 by fastening members 28 in the form of screws or bolts. The insulating plate 27 has a pair of terminals 29 and 30 secured thereto in spaced apart 15 relation and the conductors 10 and 11 are adapted to engage the terminals 30 and 29 respectively. A metal bar 31 is secured by a nut 32 to the inner face of the insulating member 27 and a complementary bar 33 is secured to the terminal 30 by a 20 nut 34. The inner or adjacent ends of the two bars 31 and 33 are disposed in spaced apart relation and the inner end of the bar 31 is provided with a socket member 34. The inner end of the bar 33 is provided with a socket member 35 which 25 is complementary to the socket 34 and the insulating member 27 is provided with an opening or socket 36 which is in axial alignment with the two socket members 34 and 35.

A short circuiting key member 37 is adapted to 30 be removably mounted in the socket formed by the two socket members 34 and 35, the key member 37 having a slightly tapered outer surface so that it may be frictionally engaged between the two bars 31 and 33. An insulating handle or 35 sleeve 38 is secured to the outer end of the key 37 so that this key may be inserted in the socket formed by the two members 34 and 35 without causing a shock to the person inserting the key. The conductor 10 is provided with a bared portion 39 within the housing 14 and this bared portion engages about the terminal 30. A nut 40 is threaded onto the terminal 30 and tightly secures the bared portion 39 about the terminal 30. The conductor 11 is provided with a bared 45 portion 41 engaging about the terminal 29 and a nut 42 is threaded onto the terminal 29 and tightly holds the bared portion 41 on the terminal 29.

During the normal use of the fire box or signaling member F the key 37 may be placed loosely 50 within the box or housing 14 or if desired may be removed entirely from the housing 14. In the event any part of the signaling apparatus in the box or housing F gets out of order the circuit 55 formed by the conductors 10 and 11 may be easily and quickly short circuited or bridged by removing the closure 18 and inserting the key 37 in the socket between the ends of the two bars 31 and 33. By short circuiting the circuit to the alarm 60 box with the key 37, the repair man will not be required to climb a pole and secure a jump wire or bridge member between the two conductors 10 and 11. Where the repair work does not require the removal of any of the signal apparatus the 65 key 37 may be left in the socket formed by the complementary socket members 34 and 35 during the time that the repair man is busy on the repair work of the signal device. However, in the event the repair man is not able to complete 70 the repair of the signal apparatus at the location

of the signal member F, the key member 37 may be left in the socket so as to bridge the conductors 10 and 11. In order to provide a means whereby other persons may be given notice that the signal member F is out of order, the closure 18 may 5 be reversed so as to expose the legend 22 on the inner face of the closure 18.

In the drawing, the housing 14 is shown mounted above the signal member F in which position the housing 14 is associated with the housing F where conductors 10 and 11 are connected to overhead wires. Where underground wires are connected to the signal member F the position of the housing 14 may be reversed or placed below the signal member F. A short circuiting or 10 bridge member constructed according to this invention may be easily and quickly secured to or connected with a signal member such as a fire alarm or similar signal device without affecting the present parts of the signal device and when 15 so connected to the signal device, the short circuiting member can easily and quickly be used for the purpose of short circuiting the associated signal device, thus eliminating a considerable amount of time expended by the repair man 20 climbing the pole or in entering the manhole or underground conduits for the purpose of short circuiting the circuits to the signal device. After 25 the short circuiting member has been installed, it will not be necessary for the workman to carry 30 climbing apparatus to climb the pole in order to repair the signal device.

What I claim is:

An electrical short-out device comprising an 35 upstanding flat supporting plate of non-conducting material formed intermediate its edges with a normally uninterrupted socket, opening at its front face, means carried by the plate for securing its other face against a supporting enclosure for the plate, a pair of spaced peripheral 40 threaded terminals carried by said plate, extending outwardly from said front face, located adjacent opposite sides of the said socket and spaced from the edges of the plate, a pair of spaced closely related inner endwise opposed flat 45 straight bars of conducting material positioned against the front face of said plate and mounted inwardly adjacent their outer ends on and in electrical contact with said terminals, said bars extending throughout in a straight plane common to both, said bars having the central portion 50 of their inner end edges formed with spaced oppositely disposed semi-circular grooves correlating to provide a normally uninterrupted socket registering at its inner end with the outer end 55 of the said other socket and aligned with said terminals, means mounted on said terminals, bearing against the front face of said bars and coacting with the said terminals and the front face of said plate for securing said bars against 60 said front face of said plate, means coacting with the terminals and with the said other means on said terminals adapted for connecting intermediate portions of the conductors of a circuit electrically to said terminals, and a removable key for 65 extension into said sockets and correlating with the wall of that socket provided by the inner end edges of said bars for electrically bridging the space between the said bars.

ROBERT B. CUMMINS. 70
